UNITED STATES PATENT OFFICE.

FRED A. HOLCOMB, OF GRAND RAPIDS, MICHIGAN.

TELEPHONE SYSTEM.

SPECIFICATION forming part of Letters Patent No. 402,929, dated May 7, 1889.

Application filed November 15, 1887. Serial No. 255,242. (No model.)

To all whom it may concern:

Be it known that I, FRED A. HOLCOMB, of Grand Rapids, in the county of Kent and State of Michigan, have invented certain new and 5 useful Improvements in Telephone Systems; and I do hereby declare the following to be a full, clear, and exact description of the invention, such as will enable others skilled in the art to which it appertains to make and use the 10 same.

My invention relates to telephone systems, and more particularly to recording mechanism for use therewith.

In the operation of telephone systems as 15 heretofore commonly constructed, when one subscriber desires to converse with another subscriber he signals the central office or station and requests to be put into communication with such party, whereupon the operator 20 at the central office connects the wires of the two circuits through the medium of a suitable switch-board and rings the bell of the party wanted. It frequently happens that the party being called fails to respond, and it 25 is desirable to provide easy and efficient means whereby such person may be notified who has called him.

It is the object of my present invention to provide mechanism whereby the subscriber 30 being called may be informed by whom he has been called.

A further object is to so construct and 35 arrange the apparatus that the operator at the central office can cause intelligible signals to be produced upon an instrument at a subscriber's station, and thus record the number of the signal of the party calling.

A further object is to provide an instrument at the central station of a telephone-ex- 40 change which can be easily and quickly thrown into electrical circuit with any subscriber, and by which the operator at the central station may cause any desired number to be recorded upon the instrument at the 45 subscriber's station.

With these objects in view my invention consists in certain novel features of construction and peculiar combinations and arrangements of parts, as will be hereinafter fully set 50 forth, and pointed out in the claims.

In the accompanying drawings, Figure 1 is an end elevation of the device with a portion

of the frame or box removed. Fig. 2 is a side view with a side of the box detached. Fig. 3 is a detached view of the ratchet mechanism. 55 Fig. 4 is a view of disk No. 10. Fig. 5 is a sectional view of the instrument which is placed at the subscriber's station.

A represents a suitable box or frame provided on the interior faces of its end pieces 60 or plates, B B', with brackets a a, which are fastened to these end plates by means of screws a', or otherwise. The brackets a a are furnished at points between their ends with perforations b, and these brackets are so secured 65 to the end plates, B B', that said perforations shall be in the same horizontal plane and serve as bearings for the journals c c' of a horizontal shaft, C. The shaft C is preferably made of non-conducting material, or it may 70 be provided with insulating-bands d, for a purpose which will be hereinafter described. The shaft C is furnished with a series of ten loosely-mounted disks, C', having their peripheries provided with toes or projections C², 75 to represent figures from one to ten, consecutively. In other words, the first disk of the series is formed with one toe, C², the second with two, the third with three toes, and so on until disk No. 10 is reached, which latter will be made with one abutment, X, several times as long as any one of the projections or toes upon the other disks, this disk 80 10 being intended to represent a cipher or number 10 when the instrument is operated 85 as presently explained.

If the shaft C be made of metal, it is preferable that the insulating-collars d be inserted 90 between the shaft and the bearing of the disks C'.

A series of spring-arms, G, are secured at one end to one of the interior faces of the containing-box A, but electrically insulated therefrom, while their free extremities, preferably bent into hook shape, are adapted to 95 make contact with the toes on the periphery of the disks C'. Each disk C' is furnished at its center with a pinion, E, which is preferably made integral with the disk and adapted to mesh with a rack-bar, F, that has a sliding 100 movement past the pinion E, as shown in Fig. 1. The rack-bars F—there being one for each disk C'—are preferably contracted somewhat at their lower ends and passed through a per-

foration in a plate of the containing-box A, or a bracket secured to the interior surface thereof. The upper ends of the bars F are each furnished with an arm or bar, F', that 5 extends first at right angles to its main portion a short distance, and then upwardly, passing through a perforation in a plate, H, which extends from end to end of the frame. The upper end of each arm F' terminates in 10 a short arm, h, that projects at right angles to the arm F', and thus returns toward the vertical plane of the rack-bar F. This arm h is provided near its free extremity with a downwardly-projecting pin, i, which is preferably furnished with a platinum point. The 15 rack-bar F, bar or rod F', and arms h will preferably be made all in one piece, there being one for each disk C'. Another series of perforations, f, is made through the plate 20 H, and each lined with a ring of suitable insulating material, g. The lower ends of a set of metallic bars or rods, I, are adapted to enter these perforations f and have a vertical sliding movement therein. The free upper 25 ends of the bars I are passed through suitable holes in the top of the containing-box A and furnished at such free extremities with knobs or buttons I', by which to operate them.

The rod I is furnished with a short arm, J, 30 at a suitable point within the box, and, projecting in a direction toward the bar F', is provided with a platinum-pointed pin, i', which normally makes contact with the pin i, as shown in Fig. 1. In order to maintain this 35 normal contact of the pins i i', I provide a coil-spring, K, that bears at its upper end against the under face of the arm J and a collar, z, upon the rod I, and preferably rests at its lower end upon the insulating-ring g, 40 the resilience of this spring tending to hold the rod I elevated and thus maintain the contact of the pins i i'.

As before stated, the disks C' are loosely mounted upon the shaft C, and are so arranged that but one disk will turn at a time, 45 the balance of the set of disks being held against rotation by the action of a series of spring-arms, L, secured at one end to the interior of the box near its bottom and bearing 50 at their other extremities against a projection, k, formed upon the disk C'. If desired, this projection k may be dispensed with, and the free ends of the spring-arms L may be bent to enter notches k' made in the peripheries of 55 the disk, or, if preferred, both projections and notches may be used.

In order to rotate any disk desired with the shaft, each disk is provided on its face opposite to its pinion E with a pin, e, extending 60 at right angles to said face, which pin is adapted to engage another pin, e', secured to the shaft C, when one of the disks is positively rotated. These pins e e' are so arranged relatively to each other that when one 65 of the disks C' is rotated positively the shaft will rotate with that disk, the others being held by their spring-arms L. All the pins on

the shaft, except the one being operated upon positively by a disk, will move away from the corresponding pins on the disks. The springs 70 L are not in any case of sufficient strength to overcome the positive action given the disks. This positive operation is given to a disk by means of the rod I and rack-bar F. By pressing upon the button I' of the rod I the lower 75 end of the latter, which is provided with an insulating-washer, m, comes into contact with the upper end of the rack-bar F and forces it downwardly, meshing with the pinion E and causing the disk to make a half-revolution. 80 This operation will bring the toes of the disk in position to make contact with the spring-arm G and cause the electric current passing through said parts to be made and broken. The disks being thus caused to make a half- 85 revolution, and the toes of the disks being in position to pass beneath the make-and-break spring G, it is necessary to provide some means by which said disk may be returned to its normal position and its toes make contact with the spring in the return of the disk. To accomplish this, a volute spring, M, is encircled about one end of the shaft C, one extremity of this spring being made fast to the shaft, while the opposite end is secured to an 90 arm, M', that is fixed to the bracket a'. This spring M is wound when the disk and shaft make their first half-revolution, and said shaft and disk are returned to their normal position by the unwinding of this spring M. 95

It will of course be understood that suitable spacing-collars, H', will be placed upon the shaft C between each two disks C'.

Mounted upon the shaft C, preferably at the same end thereof as the spring M, is an 105 escapement mechanism, N, adapted to regulate the action of the spring M when the shaft C is returning to its normal position. This escapement device may be of any desired construction; but I prefer the arrangement shown 110 in Fig. 3, in which O represents an escapement-wheel that is loosely mounted upon the shaft C, preferably near the spring M. A ratchet-wheel, O', having a collar, o, is secured to the shaft C, adjacent to the wheel O, by 115 means of set-screws adapted to pass through perforations in the collar and bear upon the shaft, as shown in Fig. 2. Pivoted to one face of the escapement-wheel O is a dog or pawl, p, which engages the teeth of the ratchet-wheel, and thus causes the wheel O to rotate with shaft C, this dog or pawl being held in engagement with the teeth of the ratchet-wheel by means of a spring, q, that is secured 120 at one end to the face of the wheel O and bears at its opposite end upon said dog or pawl.

Secured to the bracket a' at diametrically-opposite sides of the escapement-wheel O are two arms, P P, which extend at right angles 130 from said brackets to a point on line with the periphery of escapement-wheel O. A verge or pallet, Q, is pivoted upon the end of each arm P and adapted to engage the teeth of the

wheel O. These verges or pallets are preferably provided with downwardly-extending arms r r, having adjustable weights s s, by which to regulate their movement. I do not 5 claim this arrangement of escapement to be new of itself, as I am aware that the same has already been in use; hence I do not wish to limit myself to such construction, as the same may be varied without affecting the spirit of 10 my invention.

The device, being constructed as above set forth, is placed upon a table or other suitable place in the central office of the telephone-exchange and provided with electrical connections in the following manner: A wire, R, attached at one end to a grounded battery of suitable strength, is attached at its opposite end to one extremity of the spring K, that encircles the rod I. The spring-arm G is electrically connected by means of a flexible cord, S, to a plug, S', which latter is adapted to be inserted into a switch-board and thus connect a subscriber with the instrument. The instrument being thus electrically connected to 15 a suitable battery and to the apparatus of a subscriber upon which it is desired to record a signal, one of the buttons I' is depressed by the operator. This depression causes the insulated end of the rod I to make contact with the upper end of the rack-bar F, and the latter is forced downwardly, and meshing with the pinion E rotates it and the disk C'. The shaft C will rotate with the disk C', by contact of the pins e e' and cause the spring M to be 20 wound.

It will be seen by reference to Fig. 1 that the rod I has sufficient play between the pin i of arm h and the rack-bar F, so that when bar I is depressed to make contact with rack-bar F the pins i i' will separate a short distance. Now, suppose that button No. 5 has been depressed, thus causing the disk having five toes upon its periphery to make a half-revolution. The button will now be released, 25 the pins i i' making contact with each other through the action of the spring K, and the disk C' caused to rotate in the reverse direction by means of the spring M and assume its normal position. When the button I' is 30 pressed to cause the disk C' to make its first half-revolution, there will be no electric current passing through the instrument, as the pins i i' are out of contact, and hence the toes of the disks will engage the spring-arms G 35 without affecting the instrument at the subscriber's station. When the button I' is released, the pins i i' will make contact, and the current will flow from the battery through the wire R to the spring K, thence into rod or bar I. 40 The current passing from bar I flows through the pins i i' and arm J into rack-bar F, and from the latter into the disk C' through the pinion E, or in any other manner. As the disk C', which I have supposed to be the one containing five 45 toes, is rotated to assume its normal position, these toes will strike the arm G one after another and cause the current to be made and

broken five times, the current flowing from disk through arm G, cord S, and switch-board to the subscriber. This making and breaking of the current at the central office causes the instrument at a subscriber's station to be set in motion and the number to be recorded by said instrument in the form of dots upon a strip of paper. This latter-named or subscriber's instrument is preferably constructed as follows: A suitable frame is provided comprising plates A² A³, united together at their corners by means of connecting-rods A⁴. An electro-magnet, Q², is fixed to one end of the connecting-bars A⁴ between the plates A² A³, its cores extending in an upward direction parallel with the plates A² A³ and to about one-half the height of the latter. One end of the helix of this electro-magnet is connected with the ground, while the other end is connected to the line-wire. A lever, Q², pivoted between the plates A² A³ by means of trunnions Q⁴, is provided with a soft-iron armature, Q⁵, at its outer end to be attracted to the electro-magnet Q² when the latter is energized, as presently explained. A post having a cross-bar, n², is fixed to the plate A² above the lever Q², the cross-bar n² being directly over said lever. An adjusting-screw, n³, passes through one end of the cross-bar n² and normally rests against the end of the lever Q², where the latter is connected to the armature Q⁵. This set-screw serves to regulate the amount of vibration of the armature Q⁵. 50

A screw-rod, o', passes through the cross-bar n² at the end opposite to the set-screw n³ and has a spring, o², attached to its lower end, the other end of said spring being connected to the lever Q² to maintain the armature in a raised position. The inner end of the lever Q² is bent downwardly at an obtuse angle to the main portion of the lever and provided near its free end with a perforation for the reception of a pointed screw or pin, p', which is adjusted to register with the groove m² of a drum, O³, journaled between the plates, and to strike the paper passing around the drum when the armature is acted upon by the electro-magnet Q². An arm, S, is secured to the lever Q², and, projecting downwardly and forwardly, has its lower extremity bent at right angles and extended under the weighted end of a lever, K². The lever K² is pivoted to the end of a standard, K³, which is secured to the plate A³. One end of this lever is made heavier than the other and provided near said weighted end with an outwardly-projecting pin, k², which is adapted to ride upon the periphery of a disk, J², mounted on an arbor journaled between the plates A² A³, and drop into one of the notches i² of said disk by gravity at each half-revolution of the disk. The lever K² is also furnished at the opposite side of its pivot with an outwardly-projecting pin, k³, which, when the parts are in their normal position, serves as a stop for a detent-arm, l², secured to an arbor, l³, and made to rotate therewith. Said arbor, being pivoted between 100 105 110 115 120 125 130

the plates $A^2 A^3$, is provided near its opposite end with a spur-wheel, L^2 , having an escape-
ment-pallet, L^3 , arranged above it to engage
its teeth.

5 A shaft, M^2 , is pivoted between the plates $A^2 A^3$ and provided at one end with a drum or barrel for the accommodation of a coiled spring, one edge of the periphery of this drum being formed with teeth to mesh with a pin-
ion on an arbor, F^2 . The shaft M^2 is also fur-
nished with the usual pawl-and-ratchet mech-
anism to prevent the spring from accidental
unwinding. The spring may be wound by
means of a key applied to the free end of the
shaft M^2 , or otherwise, as desired. The arbor
 F^2 is further provided near its outer end with
a spur-wheel, N^2 , which meshes with a pinion
fixed on an arbor journaled in the plates A^2
 A^3 , and this spur-wheel meshes with a pinion,
20 l^1 , fixed on the arbor l^2 . The spur-wheel N^2
also meshes with a pinion fixed to an arbor,
 O^3 , journaled in the plates $A^2 A^3$. This arbor
 O^3 is furnished at or near its center with a
drum, O^4 , having a central groove, m^2 , extend-
ing around its periphery. Another arbor, P^2 ,
25 is journaled in elongated slots in the plates
 $A^2 A^3$ and held to its place by means of springs
fixed to the plates $A^2 A^3$ at one end, bearing
at their free ends upon the arbor P^2 . This
30 arbor P^2 is also furnished with a drum, P^4 ,
which is adapted to bear with a yielding press-
ure upon the drum O^3 , or upon the paper
which passes between the drums, and through
a guide fixed to the plates A^3 . A reel (not
35 shown) will be provided for this strip of pa-
per tape, which will be similar to that used
with the printing-telegraph.

The electro-magnets Q^2 are energized in
unison with the making and breaking of the
40 current at the central office and record the
number in the form of dots or spaces by means
of the pin p' striking the paper passing be-
tween the drums $O^4 P^4$. At the instant the
armature Q^3 is actuated by the magnet Q^2
45 the bent arm S comes into contact with the
under edge of the lever K^2 and raises the
same, causing the opposite end of the lever to
be lowered and the detent-arm l^2 to ride out
of contact with the pin k^3 of the lever. This
50 operation will set the mechanism into opera-
tion, and the number of the telephone-call of
a subscriber will be recorded by the mech-
anism at each half-revolution of the disk j^2 when
the apparatus at the central office is operated.

55 The above-described system is operated in
the following manner:

Subscriber "A," whose call I will assume is
35, signals the central office in the ordinary
manner and causes a drop containing the
60 number of his circuit to fall at the central
office. The operator at the central station
ascertains what party is wanted and signals
such party. Should the party (B) being called
fail to respond, the plug S will be inserted
65 into the switch-board to connect B's circuit
with the make-and-break springs G of the in-
strument at the central office. When the sub-

scriber's circuit and the signaling-instrument
at the central office are thus connected, the
button corresponding to disk 3 is first de-
70 pressed, causing the current to be made and
broken, as described, to record three dots at
the subscriber's station. When the disk 3
has completed its operation, disk 5 is operated
75 through its button I' to record five dots in or
at the subscriber's instrument in the same
manner as disk 3. Thus it will be seen that
"35" is recorded in or at the instrument of
the subscriber wanted, and notifies him that
80 a subscriber whose call is 35 has called him.

With a series of ten disks arranged as
above described it will be seen that any com-
bination of figures may be produced. While
the operator can cause any combination of
figures to be transmitted, only one disk can be
85 operated at a time, and thus confusion of
numbers can be avoided.

With the use of a telephone system such
as I have described much time may be saved,
as the instrument at the central office can be
90 operated very quickly and in very much less
time than is ordinarily required by the opera-
tor in waiting for the subscriber being
called to answer. With this system, if the
95 subscriber does not respond to his call at once
the number of the calling subscriber is pro-
duced upon the instrument of the subscriber
being called, and when said latter returns to
his instrument he is enabled to know who has
called him.

Many slight changes might be made in the
constructive details of my invention without
departing from the spirit thereof or limiting
its scope. Hence I do not wish to limit myself
to the exact details of construction shown
105 and described; but,

Having thus described my invention, what I
claim as new, and desire to secure by Letters
Patent, is—

1. In a telephone system, the combination,
110 with a recording-instrument at a subscriber's
station, of a device at the central office for
causing any desired number to be intelligibly
recorded in or at the instrument at the sub-
scriber's station, substantially as set forth.

2. In a telephone system, the combination,
115 with a device for recording intelligible sig-
nals at a subscriber's station, of an instru-
ment at the central office for operating said
recording device to produce any desired num-
ber therein, and a battery introduced into the
120 circuit of said instrument, substantially as
set forth.

3. In a telephone system, the combination,
125 with a device for intelligibly recording sig-
nals at a subscriber's station, of an instru-
ment at the central office provided with a
shaft, a series of disks having toes mounted
on said shaft, make-and-break springs with
which the toes of the disk engage to make
130 and break the current, and mechanism for
operating said disks, substantially as set
forth.

4. In a telephone system, the combination,

- with an instrument for intelligibly recording signals at a subscriber's station, of an instrument at the central office provided with a shaft, a series of disks having toes mounted upon this shaft, springs with which said toes engage, a pinion secured to each disk, rack-bars to engage said pinions, and mechanism to operate said rack-bars, substantially as set forth.
- 5 5. In a telephone system, the combination, with an instrument at a subscriber's station for recording intelligible signals, of a device at the central office having a shaft journaled therein, a series of disks loosely mounted on said shaft, each disk having a different number of toes on its periphery to represent designating-numerals from one to ten, inclusive, a disk having a wide abutment to represent the number "10" or a cipher, spring-fingers to engage said toes, and mechanism to operate the disks, substantially as and for the purpose set forth.
- 10 6. In a telephone system, the combination, with an instrument at a subscriber's station to intelligibly record a signal, of a device at the central office having a shaft journaled therein, a series of disks having toes on their periphery loosely mounted upon this shaft, a pinion upon each disk, a pin upon each disk, 15 a series of pins on the shaft to engage the pins on the disks, a series of rack-bars to mesh with the pinions to rotate the disks, and mechanism for operating said rack-bars, substantially as set forth.
- 20 7. In a telephone system, the combination, with an instrument at a subscriber's station for intelligibly recording signals, of a device at the central office having a shaft journaled therein, a series of disks having toes on their 25 peripheries mounted on said shaft, a pinion on each disk, a series of spring-arms with which the toes of the disks engage, a series of rack-bars to mesh with the pinions, upwardly-extending arms integral with said 30 rack-bars and carrying contact-points, spring-sustained rods adapted to have a sliding movement and furnished with arms to make contact with an arm of the rack-bars, and a button upon the end of each sliding rod, substantially as set forth.
- 35 8. In a telephone system, the combination, with an instrument for intelligibly recording a signal at a subscriber's station, of a device at the central office having a shaft journaled therein, a series of disks furnished with toes 40 mounted on this shaft, a series of springs to engage said toes, mechanism for rotating the disks, a spring secured to the shaft and to the frame-work of the device to cause the shaft and disks to rotate, and a ratchet mechanism 45 mounted on the shaft to regulate the action of the spring, substantially as set forth.
- 45 9. In a telephone system, the combination, with an instrument at a subscriber's station for recording intelligible signals, of a device at the central office having a shaft journaled therein, a series of disks having toes on their periphery loosely mounted on said shaft, a series of spring-arms to engage said toes to make and break the current, a pinion 50 on each disk, a series of rack-bars to operate the disks, a series of rods to operate the rack-bars in one direction, a spring on the shaft to rotate the same and the disks in the opposite direction and cause the rack-bars to rise, and an escapement mechanism to regulate the action of the spring, substantially as set forth.
- 55 10. In a telephone system, the combination, with a device for intelligibly recording a signal at a subscriber's station, of a device at the central office having a shaft journaled therein, a series of disks furnished with toes on their periphery mounted on said shaft, mechanism, substantially such as described, 60 for operating said disks to rotate them, a series of spring-arms with which the toes of the disks engage, a pin on each disk, a series of pins on the shaft to engage the pins on the disks, and spring-arms secured to the frame-work and bearing against a projection on the 65 disks to prevent the same from turning when not positively operated, substantially as set forth.
- 65 In testimony whereof I have signed this specification in the presence of two subscribing 70 witnesses.
